UNITED STATES PATENT OFFICE.

BENJAMIN ARNOLD, OF EAST GREENWICH, RHODE ISLAND.

TUBE OR CASE FOR HOLDING DRAWINGS.

SPECIFICATION forming part of Letters Patent No. 423,712, dated March 18, 1890.

Application filed March 12, 1889. Serial No. 302,961. (No model.)

To all whom it may concern:

Be it known that I, BENJAMIN ARNOLD, of East Greenwich, in the county of Kent and State of Rhode Island, have invented certain new and useful Improvements in Tubes or Cases for Holding Drawings; and I do hereby declare that the following is a full, clear, and exact description thereof, reference being had to the accompanying drawings, and to the letters of reference marked thereon, which form a part of this specification.

This invention relates more especially to the paper tubes or cases used for holding and transmitting drawings and such like articles as would be injured by being folded, and also where more perfect exclusion of air and light is desirable, as in undeveloped photographic products, &c. It is fully illustrated, so as to be readily comprehended, in the accompanying drawings.

Figure 1 shows a front elevation of the tube or case closed and sealed. Fig. 2 represents the two parts of the case separate, with a drawing inserted in each part. Fig. 3 shows the manner of holding and opening the case. Fig. 4 shows a longitudinal section of one end of the case. Fig. 5 is the same with a bar instead of a head.

The tubes or cases are made in two parts *a a*, preferably of equal length to avoid the necessity for making or keeping in stock more than one length for any particular size of case. In one end of each part *a* a head *b*, made of the same material as the tube, or thicker, if desired, is glued or otherwise fastened near the end. These heads *b* are readily punched out of sheet material in the same way as washers are made from sheet metal. The tube or case as a whole is constructed by joining two of these parts *a* together at their open ends by a strip or band *d*, of muslin or other suitable material, wrapped around the junction of the two parts, with a moist gummed surface, so that the strip will adhere to each part of the tube or case. The outer end *d'* of the strip *d* is left projecting and not gummed down to the tube like the rest of the strip. This end *d'* is left free for the purpose of affording a ready hold to the fingers when the case is to be opened, which is done by taking hold of the free end and stripping

the band off of the tube or case. (See Fig. 3.) A label *s*, for the direction of the case or as a private seal, is gummed across the band *d*, so that the band cannot be removed and the case opened without tearing the label in two.

To use the tube or case for inclosing a drawing, the drawing is first rolled up small enough and one part of the case put on it, and before letting go of the roll the other end of it is inserted in the other part of the case. Then the hand is withdrawn and the two parts of the case pushed together to meet in the middle. The band *d* is then gummed around the joint of the case, lapping far enough on each part to give the band a firm hold on it, leaving the end *d'* of the band free, as before mentioned.

To open the case, it is held in one hand and the free end *d'* of the band is taken between the thumb and fingers of the other hand (see Fig. 3) and unwound by turning the case around. Then one part of the case can be taken off and the drawings removed without any chance of injuring them; which it is sometimes almost impossible to do when heavy drawings are inclosed in paper tubes in the usual way.

This way of inclosing drawings, &c., requires much less time and material, and is more secure than the usual way of putting them in tubes and then wrapping the tubes in paper and sealing them. It has all the advantages for privacy that sealing has, as the case cannot well be opened without destroying the label. Some articles—such as sheet-music, &c., sent out by publishers—do not require the ends to be wholly closed. In such cases a bar *f* may be gummed across just inside of the ends in place of the heads, as shown in Fig. 5.

Having thus described my improvement, what I claim as my invention is—

The combination of the parts of the tube or case provided with heads, substantially as described, joined together, with a gummed strip or band having its outer end left free, substantially as and for the purpose set forth.

BENJ. ARNOLD.
